The ornamental design for a motor vehicle, toy replica and/or other replicas, as shown and described.

DESCRIPTION

FIG. 1 is a front and right side perspective view of the motor vehicle, toy replica and/or other replicas showing my new design;

FIG. 2 is a rear and right side perspective view thereof;

FIG. 3 is a left side view thereof;

FIG. 4 is a right side elevational view thereof;

FIG. 5 is a top plan view thereof;

FIG. 6 is a rear elevational view thereof; and,

FIG. 7 is a front elevational view thereof.

The dash-dot broken lines represent unclaimed boundaries for the claimed design. All broken lines shown in the drawings illustrate portions of the motor vehicle, toy replica and/or other replicas that form no part of the claimed design.
